UNITED STATES PATENT OFFICE

PATRICK J. ROONEY, OF SUGAR NOTCH, PENNSYLVANIA

SIGNAL

Application filed August 21, 1929. Serial No. 387,430.

The present invention relates to lanterns or similar devices, and has for its object the provision of an inexpensive device which may be mounted upon an automobile and manipulated to indicate the direction in which the vehicle is to proceed. The invention is illustrated in the accompanying drawings and will be hereinafter set forth and defined.

5 In the drawings:

10 Figure 1 is a front elevation of one embodiment of the invention.

Fig. 2 is a horizontal section on the line 2—2 of Fig. 1.

15 Fig. 3 is a vertical section on the line 3—3 of Fig. 2.

Fig. 4 is a side elevation of a second embodiment of the invention.

20 Fig. 5 is a sectional view taken longitudinally of the structure shown in Fig. 4, and

Fig. 6 is a transverse section on the line 6—6 of Fig. 4.

In carrying out the invention as illustrated in Figs. 1, 2 and 3, there is provided a cylind-

25 rical casing 1 having at one point in its circumferance upper and lower lens tubes 2 and 3, each of which carries a lens, the upper lens 4 being preferably green and the lower lens 5 being preferably red.

20 In the lower portion of the cylindrical casing 1, there is rotatably but snugly fitted a cylindrical member 6 which

30 rests on the bottom 7 of the casing and at one point in its circumferance is constructed with an opening 8 of the same diameter as the lens tubes.

35 Approximately midway the height of the casing 1, a horizontal slot 9 is formed therein and this slot extends half way around the casing to receive a stem 10 fixed to the ring 6 and extending through the slot, as

40 shown. Upon reference to Fig. 2, it will be noted that the ends of the slot are disposed in a vertical plane passing through the axis of the lens tubes, and it will also be noted upon reference to Fig. 3 that the stem 10 is at a

45 point diametrically opposite the opening 8 in the ring 6. Above the upper edge of the ring 6, a tube 11 is inserted through the wall of the casing and this tube receives an electric

50 bulb 12 and the terminal 13 of an electric cable so that current may be supplied to the

bulb in an obvious manner to illuminate the interior of the casing. The casing is, of course, provided with a top 14 which may be removed when renewal of the bulb is necessary or for any other reason access to the interior of the casing is desired.

55 It is intended that the interior of the casing will be polished so that the light from the bulb 12 will be reflected through the lenses in the lens tubes. Normally the opening 8

60 in the ring 6 is out of alinement with the lower lens, as shown in Fig. 3, and said lens will be obscured by the body of the ring, the light, however, being emitted through the upper

65 green lens 4. A lantern will be provided on each side of the car and the red lens on either side will be illuminated to indicate an intention to turn to that side. If it be intended

70 to turn, the ring 6 is shifted by means of the stem or handle 10 so that the opening 8 will be caused to aline with the lower lens 5,

75 whereupon said lens will be illuminated and a red light will show below the green light, thereby notifying other motorists to proceed with caution.

In the form of the invention illustrated in Figs. 4, 5 and 6, there is provided a segmental or substantially semi-cylindrical casing 15

which is secured in or on the vehicle at its chordal side, the closure 16 of the casing being secured in said side. In the opposite sides of

80 the casing are formed eight openings over which panes 17 of clear glass are secured by means of frames 18 fixed on the sides of the casing, as will be understood. The openings and the panes 17 are tapered toward the center about which the arcuate side of the casing is formed and within the casing concentric

85 therewith is mounted a frame 19 consisting of side members 20 and an opaque arch 21 connecting the side members. The side members are of a general triangular formation and are secured to a rock shaft 22 which is located

90 approximately at the center of the arcuate side of the casing and is equipped at one end with a crank handle 23, the shaft being journaled in the sides of the casing, as shown in Fig. 6 and as will be understood. The outer

95 portion of the side members of the frame 19 are divided centrally by a strip 24 extending

from the outer end of the frame toward the inner end thereof and thereby defining two openings through each side member. These openings are fitted with panes 25 of colored glass, the panes in the alined openings on the opposite sides of the frame being of the same color. One pane is red and the other green and normally the frame assumes the position shown in Fig. 5 so that neither colored pane will be disposed over or in line with the clear panes 17. The casing is illuminated by a lamp 26 fitted through one end thereof and ordinarily a clear light will be displayed inasmuch as the parts are in the position shown in Fig. 5. If it is desired to notify persons in the vicinity of the vehicle of an intention to change the course or the direction of the vehicle, the frame 19 is rocked by means of the crank 23 and the shaft 22 so that either of the colored panes 25 may be caused to aline with the clear pane 17 and thereby display a green or a red light as the case may be. When the green light is displayed, the operator will manually hold the green panes in the display position but when the red panes are to be displayed the frame may rest upon the stop pin 27 secured in the side of the casing, as will be understood. When the display of a colored light is no longer desired, the frame is rocked back to its normal position shown in Fig. 5.

It will be seen from the foregoing description that I have provided a very simple and inexpensive signal lantern which may be easily set to display either a red or a green light. In the form shown in Figs. 1, 2 and 3, the green light is constantly displayed and indicates caution while, when great care on the part of pedestrians or other motorists should be exercised, the ring 6 may be easily shifted to permit the red light to be displayed below the green light. In the form shown in Figs. 4, 5 and 6, a colored light will be displayed only when desired by the operator of the vehicle but either the red or the green light may be displayed at will. In both forms of the invention, the means for controlling the color of the light to be displayed is housed within the casing and is very simple in its arrangement so that it is not apt to get out of order.

Having thus described the invention, I claim:

A signal lantern comprising a body having a slot in its side intermediate its top and bottom, lens tubes projecting from the body, a source of illumination within the body, and a ring fitting closely but slidably within the body and having an opening and provided with a handle element extending through the slot in the body whereby the ring may be shifted to obscure a lens tube or to bring the opening in the ring into axial alinement with the lens tube.

In testimony whereof I affix my signature.
PATRICK J. ROONEY. [L. S.]
